REPEAT MECHANISM FOR CASH REGISTERS AND LIKE MACHINES

Filed July 6, 1935

FIG. 1

UNITED STATES PATENT OFFICE

2,167,771

REPEAT MECHANISM FOR CASH REGIS-
TERS AND LIKE MACHINESHubert Neureiter, Essen-Ruhr, Germany, assign-
or to The National Cash Register Company,
Dayton, Ohio, a corporation of MarylandApplication July 6, 1935, Serial No. 30,136
In Germany July 14, 1934

12 Claims. (Cl. 235—7)

This invention relates particularly to repeat mechanisms for cash registers, accounting machines and the like.

One object of this invention is to devise means whereby the amount of the preceding operation may be repeated without setting up a condition to effect said repeating in said preceding operation and without knowledge on the part of the operator that such amount is to be repeated.

10 Another object is to contrive means to automatically set up the condition for a succeeding repeat operation during the preceding operation and to provide means whereby the entering of a new amount in the machine during the succeeding operation destroys the repeat condition.

With these and incidental objects in view, the invention includes certain novel features of construction and combinations of parts, the essential elements of which are set forth in appended 20 claims and a preferred form or embodiment of which is hereinafter described with reference to the drawing which accompanies and forms a part of this specification.

In the drawing:

25 Fig. 1 is a sectional view taken just to the right of one of the amount banks and portrays in particular said amount bank and its associated differential mechanism.

Fig. 2 is a front view, partially sectioned, of 30 the mechanism shown in Fig. 1.

Fig. 3 is a fragmentary detail view of an amount bank and the repeat controlling mechanism associated therewith.

Fig. 4 is a detail view of the machine starting 35 bar and associated mechanism.

Fig. 5 is a detail view of the driving means for the differential mechanism and the zero pawl throwout shaft.

General description

40 The repeat mechanism comprising the instant invention consists of a device that is positioned commensurate with the depressed amount key or commensurate with the amount on the totalizer 45 being read or reset, said repeat device being locked in set position at the end of machine operation. Depressing an amount key in the succeeding operation renders mechanism effective that causes depression of the regular machine starting bar to move the locking means for the repeat device to ineffective position and thereby destroy the setting of said repeat device. However, in case it is desired to repeat the amount of the preceding operation all that is necessary is to de- 55 press the starting bar to release the machine for

operation and the amount of the preceding operation is automatically repeated.

A repeat operation is effected by retaining the locking means for the repeat device effective during the succeeding operation, which in turn locks 5 said repeat device in the position in which it was set in the preceding operation. Inasmuch as no amount keys are depressed the repeat device controls the positioning of the differential mechanism and causes said differential mechanism to 10 be positioned exactly as it was in the preceding operation.

The mechanism pertinent to the instant invention will now be described in detail.

Detailed description

15

The mechanism of the machine embodying the instant invention is contained between and supported by a right frame 30 and a left frame 31 (Figs. 1 and 2), said frames being secured to a 20 machine base (not shown) and braced and supported by various cross rods, bars and frames. A suitable casing or cabinet (not shown) encloses the mechanism of the machine, said cabinet being secured to the main frames 30 and 25 31 and to the machine base. The instant machine has a plurality of denominational amount banks 32 supported by a rod 33 and a channel bar 34, extending between the main frames of 30 the machine. Inasmuch as all of the amount 35 banks are substantially alike it is believed sufficient to explain only one of said amount banks and its associated differential mechanism.

Each of the amount banks 32 has a plurality of amount keys 35, and, as hereinafter described, 35 the depression of any one of which rocks a zero stop pawl 36, pivoted to the key frame 32, clockwise to move the lower end thereof out of the path of a right angled projection 37 of a main differential segment 38, rotatably mounted on a 40 bushing 39 loose on a sleeve 90 turnably mounted on a shaft 40 journaled in the frames 30 and 31.

Each of the main differential segments 38 has an associated auxiliary segment 41, also turnably mounted on the bushing 39 and having a plurality 45 of teeth in the periphery thereof, which mesh with a planetary gear 42 fulcrumed on a stud 43 secured in a differential control plate 44, loose on the bushing 39. The gear 42 meshes with a similar planetary gear 45 loose on a stud 46 50 secured in the plate 44, said gear 45 also meshing with teeth in the periphery of the differential segment 38. The plate 44 has a plurality of V-shaped notches 47 which cooperate with an alining pawl 48 secured on a shaft 49 journaled 55

in the frames 30 and 31. Also secured on the shaft 49 is an arm 50 with a roller 51 which extends within a camming groove 52 cut in the left face of a cam disk 53 secured to a shaft 54, opposite ends of which are journaled in the main frames 30 and 31. The arm 50 carries a stud 55 which cooperates with the arcuate end of an arm 56 loose on a rod 57 extending between the main frames 30 and 31. A link 58 pivotally connects the arm 56 to a lever 59 rotatable on a rod 60 supported by the frames 30 and 31.

When an amount key 35 is depressed (Figs. 1, 2 and 3) a stud 61 in said amount key in cooperation with an angular surface 62 on a control slide 63 shifts said slide downwardly or counterclockwise against the tension of a spring 64. The slide 63 is slidably mounted on the key frame 32 by means of slots therein in cooperation with two screws 65 secured in the frame 32. The slide 63 is provided with a stud 66, coacting with an ear on a lever 111 pivoted on the key frame. The lever 111 is bifurcated to engage a stud on the zero stop pawl 36. A spring 113 maintains the ear of lever 111 normally in contact with a stud 110, which positions the zero stop pawl 36 in position to arrest the differential member 38 in zero position. Downward movement of the slide 63, through stud 66, rocks lever 111 counterclockwise and the zero stop pawl 36 clockwise to release the differential member 38, as shown in Fig. 1.

Downward movement of the slide 63 also causes a stud 66 in the lower end thereof to impart counterclockwise movement to a crank 67, a shaft 68 and an arm 70, against the tension of a spring 69. The crank 67 and the arm 70 are secured to the shaft 68, opposite ends of which are journaled in the frames 30 and 31. A link 71 pivotally connects the arm 70 to a latch 72 the upper end of which is pivoted at 73 (Fig. 4) to a control slide 74, slidably mounted on a starting bar frame 75 by means of slots in said slide 74 in cooperation with screws 76 threaded in the frame 75. The frame 75 is supported by the rod 33 and bar 34. Counter clockwise movement of the arm 70 upon depression of an amount key, through the link 71, imparts similar movement to the latch 72 to hook said latch over a stud 77 in one arm of the lever 59.

Depressing a starting bar 77, mounted in the frame 75, sets the machine in motion and causes a stud 78 carried by said starting bar 77 in cooperation with an angular surface of a projection 79 of the slide 74 to impart downward or counterclockwise movement to said slide 74 against the tension of a spring 80. Downward movement of the slide 74 causes the latch 72 to rock the lever 59 counterclockwise, which movement by means of the link 58 (Fig. 1) is imparted to the arm 50.

Counterclockwise movement of the arm 50 moves the arcuate surface thereof out of the path of the stud 55, thereby freeing the arm 50 and the alining pawl 48 to the control of the cam 53. The shaft 54 and the cam 53 make one clockwise revolution each machine operation. As the cam 53 starts to rotate, the configuration of the cam groove 52 permits a spring 81 to urge the arm 50 and the pawl 48 clockwise to disengage said pawl from the V-shaped notches 47 in the plate 44.

The main differential segment 38 is actuated in one direction by a spring 96 in a manner hereinafter described, and in the other direction by means of a universal rod 83 in cooperation with

a notch 82 in said segment 38. The rod 83 is supported by symmetrical arms 84 and 85 secured to the shaft 40. The auxiliary differential segment 41 is actuated in one direction by a universal rod 87 in cooperation with a notch 86 in said segment, and in the other direction by the segment 38 through pinions 45 and 42, in a manner hereinafter described. The rod 87 extends between symmetrical arms 88 and 89 secured on opposite ends of the sleeve 90 loose on the shaft 40.

During each machine operation the shaft 40 and the rod 83 are oscillated first clockwise from the position shown in full lines in Fig. 1 to the position shown in dot and dash lines through an approximate angle of 70 degrees. The shaft 40 receives its oscillating movement from a mutilated gear 120 secured to shaft 54 (Fig. 5), which gear is normally in the plane of another mutilated gear 121 loose on shaft 40. The gear 120 is adapted to mesh with gear 121 at the proper time to rotate a crank 122 rigidly connected to gear 121. The crank 122 is connected to an arm 123 by a link 124, and the arm 123 is secured to shaft 40. Locking discs 125 and 126 associated with the mutilated gears prevent rotation thereof except at the proper time. Through the medium of a reverse gearing, consisting of gears 91, 92, 93, 94 and 95 (Figs. 2 and 5) the shaft 40 imparts a reverse operating movement to the sleeve 90 and the universal rod 87. It is therefore evident that the universal rods 83 and 87 have a reverse scissors movement and move at exactly the same speed and travel equal angular distances. Disengaging the pawl 48 from the notches in the plate 44, in the manner explained above, releases said plate for movement by the action of a comparatively strong spring 96, under control of the rod 83. One end of the spring 96 is connected to an extension 97 of said plate 44, the other end being connected to the frame of the machine.

When the machine is at rest, that is, in its home position, the segment 38 is always in its zero position, and the arm 44 and segment 41 are in the position corresponding to the value of the key depressed during the previous operation.

After the machine is released for operation, and the pawl 48 has been withdrawn from the notch in the arm 44, the machine is operated. During the first half of the machine operation the segment 38 is set in accordance with whichever one of the keys 35 is depressed, and the segment 41 is moved to its zero position by rod 87, if it was not set to zero during the previous operation.

When the universal rod 83 starts to move clockwise (Fig. 1) the spring 96, acting through arm 44 and pinion 45, rocks the segment 38 clockwise until it is arrested by the depressed key. During the clockwise movement of the segment 38, the segment 41 will tend to move clockwise therewith because of the pinions 42 and 45 which connect the two segments, but the inertia of the indicator and printing mechanism connected thereto, in a manner hereinafter described, tends to hold the segment 41 stationary. But, even if the segment does rotate clockwise during the first half of the machine operation it will only rotate until it meets the rod 87, which is at this time rotating in a counter-clockwise direction. The rod 87 will then carry the segment 41 with it until the segment is brought back to zero position at the completion of the 75

counter-clockwise movement of the rod 87. Thus at the end of the clockwise and counter-clockwise movements of the rods 83 and 87, respectively, the segment 38 and arm 44 will be 5 in the position corresponding to the value of the depressed key, and the segment 41 will be in its zero position. After the segments 38 and 41, and arm 44, are set to these positions, the pawl 48 is rocked to engage the notch of the 10 arm 44 to lock the arm against any movement during the completion of the machine operation, and therefore any subsequent movement given to the segment 38 will be transmitted to the segment 41 through gears 45 and 42.

15 When the universal rod 83 is restored, in a counter-clockwise direction, during the last half of the machine operation, it picks up the segment 38 from the position in which it was set under control of the depressed key, and restores 20 it to its zero position. Since the segment 38 is moved an extent corresponding to the value of the key depressed, this extent of movement is transmitted to segment 41 by pinions 45 and 42, thus setting the segment 41 to a position 25 corresponding to the value of the depressed key. Therefore, when the machine comes to rest, the segment 38 is in its normal, zero, position, and the segment 41 and arm 44 are in a position corresponding to the value of the depressed key, 30 the latter being locked in such position by the pawl 48. Differential positioning of the segment 41 is transmitted by means of a gear 100 (Fig. 1) to a corresponding type carrier and by means 35 of the gear 100 and an intermediate gear 101 differential positioning of said segment 41 is transmitted to an indicator roller 102 for that particular amount bank. Return movement 40 counterclockwise of the main differential segment 38 from a second position to zero position also accumulates the value of the depressed amount key in the corresponding wheel of the selected totalizer (not shown). Clockwise travel 45 of the plate 44 (Fig. 1) is limited by means of a surface 103 on said plate contacting an abutment 104.

In case it is desired to repeat the amount of the preceding operation all that is necessary is for the operator to set the machine in motion by depressing the starting bar 77 (Fig. 4), as 50 the machine is always conditioned for a repeat operation, and this condition remains effective until an amount key is depressed. The worth of such a repeat mechanism is readily appreciated when it is understood that it is unnecessary for the operator to have knowledge of a succeeding repeat operation during the immediately preceding operation, and that it is likewise unnecessary for the operator to manipulate any special devices in order to effect a repeat 55 operation. All that is necessary is the depression of the usual starting bar, which is regularly used for setting the machine in motion in all operations.

Near the end of an adding operation the 60 depressed amount keys are automatically released in the usual manner, and the spring 64 (Fig. 1) returns the slide 63 upwardly to normal position as shown in Fig. 3. This permits the spring 69 to disengage the hook of the latch 72 from the stud 77 and a spring 105 returns the lever 59 and the arm 56 clockwise to effective 65 position, as here shown, to move the arcuate surface of the arm 56 in the path of the stud 55 to lock the alining pawl 48 in one of the notches 70 47 to retain the plate 44 in the position in which

it was set in the preceding operation. Clockwise movement of the lever 59 and the arm 56 under the influence of the spring 105 is limited by means of a stop stud 106.

It is, therefore, obvious that when no amount 5 key is depressed the latch 72 is ineffective and subsequent depression of the starting bar 77 (Figs. 1 and 4) and consequent downward movement of the slide 74 and the latch 72 imparts no movement to the lever 59 and the arm 56. 10 Consequently the pawl 48 remains locked in the plate 44 and retains said plate in the position in which it was set in the preceding operation and said plate 44 through the auxiliary segment 41 controls the positioning of the main segment 15 38 to repeat the amount of the preceding operation. As a specific example, let us assume that the auxiliary segment 41 and the plate 44 were moved to the "2" position in the preceding operation. In a subsequent repeat operation the 20 pawl 48 retains the plate 44 in the "2" position and the zero stop pawl 36 is rocked to ineffective position by mechanism hereinafter described. Inasmuch as the spring 96 is ineffective due to the locking of the plate 44, the 25 segments 38 and 41 remain stationary during the initial movement of the universal rods 83 and 87 until the rod 87 contacts the recess 86 and returns the segment 41 from the "2" position to zero position. This return movement of 30 the segment 41 is transmitted by means of the planetary gears 42 and 45 to the main differential segment 38 and said segment is moved in a clockwise direction exactly the same number of steps as the auxiliary segment 41 is returned 35 counterclockwise. After the segment 38 is thus adjusted in the position in which it was set in the preceding operation the corresponding wheel of the selected totalizer is engaged therewith and return movement counterclockwise of the 40 universal rod 83 causes the amount of the preceding operation to be accumulated on the wheel of the selected totalizer. Return of the segment 38 from the "2" position to zero position by the rod 83 through the planetary gears 45 and 42 45 imparts a similar reverse movement to the auxiliary segment 41 to position the type carrier and the indicator segment for that particular denomination commensurate with the repeated amount.

Obviously the result of a preceding total taking 50 operation may be repeated and added in a selected totalizer the same as the result of a preceding adding operation, the only difference being that instead of the differential mechanism 55 being positioned under the influence of depressed amount keys said differential mechanism is positioned under influence of the wheels of the totalizer being read or reset.

As above mentioned, the zero stop pawls 36 60 are rocked into ineffective position during repeat operations. For this purpose, each zero stop pawl 36 is provided with a stud 130 engaged by a finger on a lever 131 pivoted on the shaft 68. A lever 131 is provided in each key 65 bank and the levers are all connected to move as a unit by a rod or bail 132, which extends through all of the levers 131. The lower end of lever 131 is provided with a stud 133 held engaged with a cam 134 by a spring 135. The cam 70 134 is secured to a shaft 136, which receives one rotation each machine operation by a train of gears 137, 138, 139, and 140, on shafts 136, 104, 49, and 54, respectively. Thus, when the shaft 136 starts rotating at the beginning of a ma- 75

chine operation, the cam 134 releases the arms 131 to the action of spring 135, and the arms 131 thereby withdraw all of the zero stop pawls 36 from their effective positions, provided no amount key has been depressed. If any amount key has been depressed, the associated slide 63 is lowered to position a flange 129 thereon into the path of its associated lever 131, thus blocking movement of all the levers 131. When no amount key is depressed, all the zero stop pawls 36 are withdrawn to permit the differentials to be controlled to repeat the last entry. A control similar to the above means for controlling the zero stop pawls 36 is disclosed in the patent to Breitling, No. 2,116,779, issued May 10, 1938.

While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims which follow.

What is claimed, is:

1. In a machine of the class described having a plurality of amount keys, the combination of a member differentially positioned under control of the amount keys; means rendered effective in each machine operation to lock the member in set position for a subsequent repeat operation; a manipulative device; and means operated by the amount keys to connect the locking means to the manipulative device to cause said manipulative device to disable the locking means to prevent the retention of the member in pre-set position during an operation of the machine in which an amount key is depressed.

2. In a machine of the character described having a plurality of amount keys and a starting device, the combination of a member differentially positioned under control of the amount keys; means effective in each machine operation to lock the member in set position and to retain said member locked in a subsequent repeat operation; and means whereby depression of an amount key for a subsequent operation connects the locking means to the starting device to cause said starting device to disable the locking means when a new amount is entered on the keyboard in a subsequent operation.

3. In a machine of the character described having a plurality of amount keys and differential mechanism controlled thereby, the combination of means normally effective in each machine operation to control the differential mechanism for a subsequent repeat operation; a normally ineffective means to disable the control means; and means operated by the depression of an amount key for a subsequent operation to render the disabling means effective to disable the control means.

4. In a machine of the class described, the combination with a plurality of amount keys, differential mechanism controlled thereby, and means to start the machine operating, of means normally effective in each machine operation to control the differential mechanism for a subsequent repeat operation; means operable by the starting means to disable the control means in a subsequent operation, said disabling means normally disconnected from said starting means; and means whereby the depression of an amount key in a subsequent operation connects the disabling means to the starting means.

5. In a machine of the class described, the

combination with a plurality of amount keys, differential mechanism controlled thereby, and means to start the machine operating, of means normally effective in each machine operation to control the differential mechanism for a subsequent repeat operation; means operable by the starting means to disable the control means in a subsequent operation, said disabling means normally disconnected from said starting means; means including a latch to connect the disabling means to the starting means; and means operable by the depression of an amount key to move the latch to effective position.

6. In a machine of the class described having an actuator for adding amounts, and amount keys to control the actuator, the combination of a member, means to normally adjust the member under control of the actuator to a position corresponding to an amount added by the actuator, means to lock the member in said adjusted position at the end of an adding operation, said member adapted, when so locked, to control the positioning of the actuator during an operation of the machine wherein no amount keys are depressed, normally ineffective means to actuate the lock means to unlock the member whereby the actuator may be controlled by a depressed amount key, and means operated by the depression of an amount key to render the last-named means effective.

7. In a machine of the class described having an actuator for adding amounts, and amount keys to control the actuator, the combination of a motor bar to release the machine for operation, means to adjust the member under control of the actuator to a position corresponding to an amount added by the actuator, means to lock the member in said adjusted position at the end of an adding operation, said member adapted, when so locked, to control the positioning of the actuator during an operation of the machine wherein no amount keys are depressed, and means controlled by the depression of any amount key and operated by the depression of the motor bar to actuate the lock to unlock the member, whereby the actuator is controlled by the depressed amount key.

8. In a machine of the class described having an actuator for adding amounts, and amount keys to control the actuator, the combination of a motor bar to release the machine for operation, an adjustable member, means to adjust the member under control of the actuator to a position corresponding to an amount added by the actuator, means to lock the member in said adjusted position at the end of an adding operation, said member adapted, when so locked, to control the positioning of the actuator during an operation of the machine wherein no amount keys are depressed, a coupling link, connections between the coupling link and the amount keys to connect the link to the lock means upon depression of any amount key, and means between the link and the motor bar to actuate the lock means to unlock the member by the depression of the motor bar whenever any amount key is depressed prior to depressing the motor bar, whereby the member is freed to be adjusted under control of the actuator and the depressed amount key.

9. In a machine of the class described, the combination of an actuator, amount keys to control the actuator, a member normally set under control of the actuator, means to automatically lock the member in set position at the end of the machine operation, said member

adapted when locked, to control the adjustment of the actuator for a repeat operation, normally ineffective means to unlock the member, and means actuated by the depression of an amount key to render the last-named means effective.

- 5 10. In a machine of the class described, the combination of an actuator, amount keys to control the actuator, a member normally set under control of the actuator, means to automatically lock the member in set position at the end of the machine operation, said member adapted when locked, to control the adjustment of the actuator for a repeat operation, a machine release means, means normally disconnected from the machine release means to actuate the lock to unlock the member prior to a machine operation, and connections operable by the depression of an amount key to connect normally disconnected means to the machine release means, whereby the member is unlocked when the machine release means is actuated for an operation of the machine in which any amount key is depressed.
- 10 15 20 10 15 20

11. In a machine of the class described, the

combination with a plurality of amount keys and differential mechanism controlled thereby, of means normally effective in each operation to control the differential mechanism for a subsequent repeat operation; a normally ineffective means to disable the control means; and means operated by the depression of an amount key to render the disabling means effective to disable the control means.

12. In a machine of the class described, the combination with a plurality of amount keys, differential mechanism controlled thereby, and means to start the machine operating, of means normally effective in each operation to control the differential mechanism for a subsequent repeat operation; connections operable by the starting means but normally uncoupled from the starting means to actuate certain elements of the control means to render the control means ineffective; and means operated upon depression of any amount key to couple said connections to the starting means.

HUBERT NEUREITER.
